CLAIM

The ornamental design for an electric pallet truck, as shown and described.

DESCRIPTION

FIG. 1 is a top, front and right side perspective view of an electric pallet truck, showing my new design;
FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the portion labeled "9" in FIG. 1.

The broken lines in the drawings depict portions of the electric pallet truck that form no part of the claimed design. The dot-dash broken lines define the boundaries of the enlarged views that form no part of the claimed design.
